Fig. 1.

Fig. 2.

FIGURE 1 is a perspective view of a foldable traversing screen according to a first embodiment of my new design;

The rear of each of the screens illustrated is substantially the same as the front thereof shown except in reverse and is therefore not shown.

This application is a continuation of my copending applications Serial No. D. 68,641, filed February 5, 1962 for "Foldable Traversing Screen," now abandoned, and Serial No. D. 68,644, filed February 5, 1962 for "Foldable Traversing Screen," now abandoned.

I claim:

The ornamental design for a foldable traversing screen, substantially as shown and described.
